(57) **CLAIM**

The ornamental design for a heat pump type heat source unit, as shown and described.

DESCRIPTION

FIG. 1 is a perspective view of a heat pump type heat source unit showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines in the drawings illustrate portions of the heat pump type heat source unit which form no part of the claimed design.
